[57] CLAIM

The ornamental design for combined moulding, leg and skirt trim for casegoods, as shown and described.

DESCRIPTION

FIG. 1 is a front, left side perspective view of combined moulding, leg and skirt trim for casegoods showing my new design, the right side being a mirror image thereof;

FIG. 2 is a front elevational view thereof;

FIG. 3 is a front, right side perspective view of second embodiment of the combined moulding, leg and skirt trim for casegoods shown in FIG. 1, the left side being a mirror image thereof;

FIG. 4 is a front, left side perspective view of a third embodiment of the combined moulding, leg and skirt trim for casegoods shown in FIG. 1, the right side being a mirror image thereof; and,

FIG. 5 is an enlarged detailed elevational view of the bottom left leg.

The broken lines shown on the top rear of each casegood indicate the boundary of the claimed design; the other broken lines shown throughout the views are for environmental purposes and form no part of the claimed design.
